UNITED STATES PATENT OFFICE.

ACALLIOUS ELBERT SHUTTERLY, OF INDIANAPOLIS, INDIANA.

MEASURING SPOON OR DIPPER.

1,348,591.

Specification of Letters Patent.

Patented Aug. 3, 1920.

Application filed May 17, 1919. Serial No. 297,740.

To all whom it may concern:

Be it known that I, ACALLIOUS ELBERT SHUTTERLY, a resident of Indianapolis, in the county of Marion and State of Indiana, have invented a new and useful Improvement 5 in Measuring Spoons or Dippers, of which the following is a specification.

The invention relates to measuring devices for measuring out quantities of dry material. The object of the invention is to provide a device of simple construction whereby the requisite amount of material 10 can be readily supplied.

In the accompanying drawing Figure 1 is a plan view of the device; Fig. 2 is a longitudinal section thereof on the line 2—2, Fig. 1; and Figs. 3 and 4 are transverse sections taken, respectively, on the lines 3—3 and 4—4, Fig. 1.

20 The device comprises a bowl 5 of any desired shape and of a size so that when level full it contains the requisite amount of material. This bowl has integral therewith a shank 6 and handle 7, said shank being provided with a longitudinal hole 8 and the handle being in loop form as shown, provided on the inner faces of its two side portions with grooves 9, and provided in its end portion with a slot 10 of such width that 25 its ends are flush with the bottoms of the grooves 9 and of a height equal to the width of the grooves 9. Slidable in the hole 8 in the shank 6 is a rod 11 provided at its outer end with the arms 12 which form a striking-off device to strike off surplus material in the 30 bowl 5. Connected to the inner end of the rod 11 is a ring 13 of such diameter that it has a sliding fit in the grooves 9 in the handle, and which ring is suitably connected 35 to the rod 11, such as by having an open ring with conical ends fitting in conical depressions 14 in the sides of the rod 11, as shown in Figs. 1, 2 and 4, in the same manner that a watch bow is connected to the 40 stem.

To assemble the parts, the rod 11 is slipped endwise from the forward end of the device through the hole 8 in the shank; the ring 13 is inserted into the handle through the 45 end slot 10, and its ends are then sprung into the sockets in the rod, thus securely fastening said parts together. The ring 13 serves as a convenient means for reciprocating the rod 11 and strike-off arms 12, and 50 also by its engagement in grooves 9 prevents

the rod 11 from rotating and therefore holds the striking-off device 12 in proper position.

In the use of the device the striking-off measuring device 12 and ring 13 will be in rearward position, when the handle is 60 grasped and a portion of the material to be measured is scooped up in the bowl 5. A thumb or finger of the hand grasping the handle will be in the ring 13, and by means thereof the striking-off arms are reciprocated outwardly, thus striking off from the bowl the excess material which is heaped therein, striking the contents to a level surface and thus getting an exact measured 65 quantity of material.

70 The device described is of simple construction, is easy to keep clean and sanitary, is easy and convenient to operate, and insures accurate measurements of the amount of material, thus preventing overdoses or 75 the use of excess material.

I claim:

1. A device of the character described, comprising a bowl, a handle therefor provided with a longitudinal hole, and a rod 80 reciprocable but non-rotatable in said hole and provided at its outer end with striking-off arms projecting laterally over the bowl.

2. A device of the kind described, comprising a bowl, a handle therefor provided 85 with a longitudinal hole, a rod reciprocating in said hole and provided at its outer end with striking-off arms projecting laterally over the bowl, and co-acting means between said rod and handle for preventing rotation 90 of said rod.

3. A device of the kind described, comprising a bowl, a handle therefor provided with a longitudinal hole and with a longitudinal groove, and a rod mounted to reciprocate in said hole and provided at its outer end with portions extending laterally over the bowl and at its inner end with a member 95 engaging the grooves in the handle to prevent rotation of said rod.

4. A device of the character described comprising a bowl, a handle therefor provided with a longitudinal hole, a rod reciprocating in said hole and provided at its outer end with portions extending laterally 105 over the bowl and at its inner end with a finger-piece for reciprocating the rod, said finger-piece having a sliding interfitting engagement with the handle to prevent rotation of said rod.

5. A device of the kind described, comprising a bowl, a handle therefor provided with a longitudinal hole and outwardly of the same with parallel arms provided on their facing sides with longitudinal grooves, a rod mounted to reciprocate in said hole and provided at its outer end with portions extending laterally over the bowl, and a ring

secured to the inner end of said rod and engaging the groove in the arms of the handle 10 and serving to prevent rotation of the rod and as a means to reciprocate said rod.

In testimony whereof, I have hereunto set my hand.

ACALLIOUS ELBERT SHUTTERLY.
